(57) **CLAIM**

The ornamental design for a steering control support, as shown and described.

DESCRIPTION

FIG. 1 is a right, top, front, perspective view of a steering control support embodying our new design;

FIG. 2 is a top plan view thereof;

FIG. 3 is a right side elevational view thereof;

FIG. 4 is front elevational view thereof;

FIG. 5 is a rear elevational view thereof;

FIG. 6 is a left side elevational view thereof; and,

FIG. 7 is a bottom plan view thereof.

The broken lines in the drawings represent unclaimed environmental matter.

In a preferred embodiment, the nature of this product is a support arm steering control, such as a stalk for a steer tiller for a lift truck and the like.

1 Claim, 3 Drawing Sheets

FIG. 6

FIG. 7
